Dec. 1143

Philo B. Gilbert, of New York, N. Y.
Letters Patent No. 1143. Dated Sept. 6, 1859.

The schedule referred to in these ^{www} Letters Patent and making part of the same.

To all whom it may concern:

I do know that, William B. Gilbert of the City, County and State of New York, have invented or produced a new and original design for the handles of Spoons and Forks, which I call "The Second Time Pattern", and I do hereby declare the following to be a full, clear and exact description of the same, reference being had to the accompanying drawings, making a part of this Specification, in which

Fig. 1, 2. and 3, represent in perspective table Spoons ornamented after my design, and

Fig. 4. and 5, represent in perspective the same ornamental work applied to the handles of forks, fig: 4. representing a view of the rear or back, and fig: 5. of the front of the forks.

My design is composed of the following ornaments, viz: first a shield *a*, enclosed at its sides by a moulded bead *b*, which runs into foliage *c*, at, and around, the top marginal portion of the handle, with an acorn *e*, between the foliage tracery.

At the lower end of the shield the beading is turned into volutes, below which there is pendent foliage *f*, which completes that part of the ornament.

Near where the handle *A*, joins the bowl *B* of the spoon, and on the front of the handle is a lyre-shaped piece of foliage *m*, and the margins of the handle between and around the ornaments may have a fine thread raised upon it.

The same letters of reference indicate the same ornaments upon the handles of the forks fig. 4 and 5. and, in addition thereto, in fig: 4, which represents the back of the handle, there is on its heel an ornament *n*, composed of foliage and tracery, enclosing a plain ground *o*. This ornament *n*, may be upon the spoon as well as upon the fork handles.

Having thus described the character of my design what I claim is the ornamental configuration herein represented, as applied to the handles of Spoons and Forks, as set forth.
